DES. 1969

Henry Damon, of Boston, Mass.

Letters Patent No. 1969 Dated July 13, 1864

Antedated June 7th 1864

Design for a Trade Mark

The Schedule referred to in these Letters Patent and making part of the same.

to all Persons to whom these Presents shall come

Be it known that, Henry Damon, of Boston, in the County of Suffolk, and State of Massachusetts, have invented or produced a new and original design for a Trade Mark; and I do hereby declare the same to be fully described in the accompanying specification and represented in the accompanying drawing.

The design in question consists mainly of the representation of a shield having parallel sides, a curved or concave top, and a notched semicircular bottom as illustrated in the said drawing, but of the words invented by the Companys arranged within such shield. This design may be enclosed within a border which may be ornamented to such an extent as may be desirable.

I claim as my invention The design for a trade mark as above described and as represented in the accompanying drawing.
